LAWN CULTURE TRAILER

Joseph Coopersmith, New York, N. Y., and Francis W. Ruzicka, Florham Park, N. J., assignors to Liquilawn, Inc., New York, N. Y., a corporation of New York

Application November 28, 1955, Serial No. 39,054

Term of patent 14 years

(Cl. D14—3)

FIG-1

We claim:

The ornamental design for a lawn culture trailer, substantially as shown.
